CLAIM

The ornamental design for a portion of a shoe upper, as shown and described.

DESCRIPTION

FIG. 1 is a front perspective view of a shoe showing my new design of a portion of a shoe upper;

FIG. 2 is a rear perspective view thereof; and,

FIG. 3 is a side elevational view of one side thereof.

The broken line showing immediately adjacent to the shaded area represents an unclaimed boundary of the design. The broken line showing of the remainder of the shoe is for illustrative purposes only and forms no part of the claimed design. The use of multiple shading techniques in the drawings reflects a contrast of appearance only and does not depict any particular color, texture, or material.

1 Claim, 3 Drawing Sheets
